UNITED STATES PATENT OFFICE

150,497

DESIGN FOR A PUTTING AID DEVICE
FOR A GOLF CLUB

Carl F. Forsell, Rockford, Ill.

Application March 15, 1946, Serial No. 127,541

Term of patent 3½ years

(Cl. D34—5)

To all whom it may concern:

Be it known that I, Carl F. Forsell, a citizen of the United States, residing at Rockford, in the county of Winnebago and State of Illinois, have invented a new, original, and ornamental Design for a Putting Aid Device for a Golf Club, of which the following is a specification, reference being had to the accompanying drawing, forming part thereof.

In the drawing:

Figure 1 is a perspective view of a putting aid device as applied to a golf club head embodying my new design;

Figures 2 and 3 are top and side views, respectively, thereof; and

Figure 4 is an enlarged section taken on the section line 4—4 of Figure 3.

I claim:

The ornamental design for a putting aid de-

vice for a golf club, substantially as shown and described.

CARL F. FORSELL.
